UNITED STATES PATENT OFFICE.

LAUREN S. BEARDSLEY, OF NAUGATUCK, CONNECTICUT.

DESIGN FOR AN INSULATOR-BRACKET.

SPECIFICATION forming part of **Design No. 25,177**, dated February 18, 1896.

Application filed December 20, 1895. Serial No. 572,794. Term of patent 14 years.

To all whom it may concern:

Be it known that I, LAUREN S. BEARDSLEY, a citizen of the United States, residing at Naugatuck, in the county of New Haven, State of Connecticut, have invented and produced a new and original Design for Fastening and Supporting Insulator-Brackets for Electric Wires, of which the following is a specification, reference being had to the accompanying drawing, forming a part of this specification.

The design consists in an insulator-holder having two upright upwardly-projecting pins spirally formed on their upper ends and at their lower ends bent to form a cross-bar from which project both upward and downward a middle bar having its upper and lower

ends split and perforated, the whole being formed of an integral and single piece of material.

I have illustrated the invention in the accompanying drawing, which is a vertical elevation of the same.

What I claim as new, and desire to secure by Letters Patent, is—

The design for an insulator-holder substantially as shown and described.

In testimony whereof I affix my signature in the presence of two witnesses.

LAUREN S. BEARDSLEY.
